N. Y., A CORPORATION OF NEW YORK

SANDPAPERING MACHINE

Application filed February 6, 1931. Serial No. 513,794.

The invention relates to an improvement in sand papering machines and more particularly to an improvement in machines of this character for sand papering or smoothing toilet seats or other similar articles of regular or irregular contour. The object of the invention is to produce a simplified machine which will rapidly and efficiently sand paper or smooth such articles as toilet seats and covers which are commonly composed of wood or other easily abradable substance. To this end the invention consists in the improved sand papering machine fully described hereinafter and particularly pointed out in the claims.

The preferred form of the invention is illustrated in the accompanying drawings in which Fig. 1 is an end elevation of the improved sand papering machine; Fig. 2 is a partial front elevation of the machine as illustrated in Fig. 1; Fig. 3 is a view similar to Fig. 1, but with parts broken away, and showing the operating parts in normal or inoperative position; Fig. 4 is a plan view of a seat in position to be operated upon and showing in section the lower ends of the lever arms for controlling the endless sand papering belt; Fig. 5 is a detail illustrating how the machine operates upon a portion of the article in which the inner and outer edges are of different contour; Fig. 6 is a view similar to Fig. 5 to illustrate the adjustment of the lever arms to operate on a solid article; and Fig. 7 is a top plan of the article shown in Fig. 6.

The improved sand papering machine as illustrated in the drawings comprises an endless belt 10 coated on its outer surface with comminuted flint, emery or other abrasive substance 11. The endless belt 10 passes over and is driven by a pulley 12 fixed on one end of a shaft 14 journaled in the upper end of upright frames 15, only one of which is shown. The frames are held in fixed relation by the cross rods 16. Power is applied in any convenient manner to drive the shaft 14. The lower section of the endless sand papering belt 10 passes under and in contact with the guide wheels 17 and 18 supported respectively on the lower ends of the lever arms 19

and 20 pivoted on substantially the same plane, as at 21 on the frame 15.

The article to be sand papered or otherwise operated upon by the machine of the present invention is supported during the sand papering operation upon a table or form 23 having a general outline of the article to be operated upon, in the illustrated form of the invention, either a toilet seat 24 or a cover 25 therefor. The article is conveniently held in place on the form 23 by means of pins 26 which can be arranged to penetrate the under surface of the article at points which either will be covered up or made inconspicuous in the finished article. The form 23 is annulus-like in shape and is supported on a base plate 28 secured to the upper end of a vertically arranged shaft 29 rotatively and slidably mounted in the bearing 30 secured to the frame 15. The shaft 29 is hollow and slidably embraces at its lower end a vertically arranged shaft 31 journaled in the bearing 32 supported on the frame 15. The upper end of the inner shaft 31 is provided with a series of keys 33 which mesh with a corresponding series of keyways in the inner surface of the lower end of the outer shaft 29. To the lower extremity of the inner shaft 31 is fixed a bevel gear 34 which is driven by a gear 35 mounted on one end of a shaft 36 journaled in the machine frame and driven from a pulley 37 in turn driven from a pulley 38 mounted on the shaft 14.

When the parts are in normal or inoperative position, as shown in Fig. 3, the plate 28 and form 23 are lowered to bring the article below the lower ends of the lever arms 19 and 20 so that the finished article may be removed and an untreated article placed on the form 23. The form 23 is lowered and raised by means of a handle 40 journaled on the lower rod 16 between the collars 41 fixed thereon. The handle 40 forms part of a bell crank the other arm 42 of which is bifurcated at its outer end and loosely embraces a vertically arranged rod 43 supported for sliding movements at its lower end in a bracket 44 projecting from the inner face of the frame upright 15. The bifurcated outer end of the crank arm 42 is slotted to engage with a pin 100

45 fixed in the rod 43. Mounted on the rod 43 is an arm 46 the outer end of which is arc-shaped and loosely engages in a grooved collar 47 fixed on the lower end of the outer shaft section 29. The above described construction is such that as the handle 40 is pushed inwardly the rod 43 and shaft 29, with the form 23 thereon, are lowered to the position shown in Fig. 3, whereas when the handle 40 is pulled outwardly the rod 43 and shaft 29 are raised to bring the form 23 with the article thereon to the position shown in Figs. 1 and 2.

When the form 23 is raised to bring the article in position to be operated upon by the endless sand papering belt 10, the belt supporting and guiding wheels 17 and 18 are brought into the position shown in Fig. 1 to provide a slack in the belt 10, and when the form 23 is lowered into inoperative position the guide wheels 17 and 18 are spread apart to bring the lower section of the belt 10 to a taut or horizontal position, as shown in Fig. 3. The means for operating upon the lever arms 19 and 20 to swing the wheels 17 and 18 toward and from each other when the form 23 is raised and lowered, comprises a roll 49 pivoted on the outer end of a pin 50 the inner end of which is fixed in the upper end of a bent rod 51 adjustably secured at its lower end in a block 52 in which the upper end of the rod 43 is also adjustably secured. To the upper extremity of the rod 43 is attached a wire 53 which passes over a wheel 54 journaled on the bracket 55 supported from the upper cross rod 16. To the lower free end of the wire 53 is attached a counter-weight 56. The middle section of the pin 50 passes through a grooved block 57 which slides in a vertical slot 58 formed in the frame 15. When the handle 40 is thrown inwardly to depress the rod 43 and lower the parts connected with it the roll 49 is brought down against the cam surfaces 60 formed on the upper enlarged ends of the lever arms 19 and 20. When the parts are in operative position, as shown in Fig. 1, the two cam surfaces 60 are obliquely arranged and face each other to form a broad V the sides of which slightly overlap at their inner edges, the upper ends of the lever arms 19 and 20 being in overlapping relation, as is clearly indicated in Fig. 2. The lowering of the roll 49 when the handle 40 is pushed inwardly brings the roll 49 against the cam surfaces 60 and causes the upper ends of the arms 19 and 20 to be spread apart, as shown in Fig. 3, thereby moving the lower ends of the arms 19 and 20 outwardly and freeing the lower section of the belt 10 from the work, which is simultaneously lowered. When the handle 40 is moved outwardly, thereby raising the rod 43 and the roll 49 the contraction spring 61 connecting the lower ends of the lever arms 19 and 20 acts to pull the guide wheels 17 and 18

toward each other so that a fold or loop 62 may be formed in the belt 10 to act upon the article to be sand papered.

Assuming that it is desired to smooth or round off the two upper edges of a toilet seat 70 of usual form, the operator places the seat on the form 23 and pushes downwardly until the lower surface of the seat presses tightly against the upper surface of the form 23, with the pins 26 penetrating the under surface of the seat far enough to hold it firmly in place during the sand papering operation. In this connection it will be noted that the stresses on the seat during the sand papering operation are generally in a downward direction, 80 and that consequently only a slight brace is necessary to hold the seat against swerving laterally. Having placed the seat in proper position on the form 23 the operator pulls the handle 40 outwardly to the position shown 85 in Fig. 1, thereby raising the form 23 with the seat thereon and at the same time disengaging the roll 49 from the upper ends of the lever arms 19 and 20 to permit the spring 61 to pull the belt guiding wheels 17 and 18 toward each other to form a loose loop in the belt between them at the point at which a section of the seat is positioned between the wheels, all as clearly indicated in Fig. 1. As the operator pulls the handle 40 outwardly 90 or toward him, he also connects the shaft 14 with the source of power, thereby causing the belt 10 to travel lineally and the shaft 29 with the parts mounted thereon to rotate. Although the usual form of toilet seat is slightly oval or elongated, nevertheless the flexible endless abrading belt accommodates itself perfectly to the upper, partly rounded surface of the toilet seat and as the form 23 continues to rotate wears away by the abrading 100 action of the belt 10 the surplus material on the two upper edges of the seat until a properly rounded contour is given to the upper surface of the annulus-like seat.

Toilet seats of usual form or construction are not perfect ovals but are usually provided with two corners at their rear end. In order that these two more or less sharp corners may not be flattened out too much, the form 23 is provided at these points with a cam path 64, and the guide wheel 17 which is on the outer edge of the seat, is mounted on a flat bar-like arm 65 yieldingly and slidingly connected with the lower section 66 of the lever arm 19. The section 66 of the lever arm 19 is provided with two lateral guide members 67 which loosely embrace the upper end of the bar 65 which is provided with a pin 68 to which is attached one end of a contraction spring 69 the other end of which is attached to a pin 70 fixed in the lower end of the lever arm section 66 and projecting through a slot 71 in the bar 65. The lower extremity of the slideable arm section 65 carries a roll 72 which travels on the cam path 64. At the corner 110

points 75 of the toilet seat 24 the cam path 64 rises, as clearly indicated at 77 in Fig. 5 and the roll 72 travels up the incline thereby pushing upwardly the movable arm section 65 which pulls out or elongates the spring 69. Thus less pressure is exerted by the raised guide wheel 17 on the belt and the corners 75 are not flattened out unduly. When the corner sections 75 are passed the roll 72 descends to normal and thereupon the spring 69 contracts to pull the movable arm section 65 downwardly to restore the guide wheel 17 into the same plane as the guide wheel 18.

When the seat 25 is to be sand papered, the guide wheel 18 is raised above the upper surface of the seat, as shown in Fig. 6, and for this purpose the lower end 74 of the lever arm 20 is pivotally connected, as by the bolt 76, with the upper section of the arm 20 so that the lower section 74 may be held in a substantially horizontal position. The guide wheel 17 however continues in the same relation with respect to the cover 25 that it held with respect to the seat 24 so that the edge of the cover is properly rounded by the abrading action of the traveling belt 10 as the form 23 rotates. In the case of the cover 25 also, the roll 72 rides up and down the inclines 77 located opposite the rear corners 78 of the cover to ease the pressure on the belt at these points.

To aid the action of the traveling abrading belt 10 as the form 23 rotates the lower ends of the lever arms 19 and 20 are provided with the horizontally rotatable wheels 79 which contact with the outer and inner surfaces of the form 23 as the latter rotates, the rolls 79 being held in contact with the form 23 under the action of the spring 61. To keep the endless abrading belt taut as it travels over the pulley 12 and guide wheels 17 and 18, an idler 80 is provided mounted on the outer end of a spring pressed arm 81.

It will be understood that the action of the machine is largely under the control of the operator, and that after he places an article on the form 23 to be sand papered and moves the handle 40 outwardly to raise the form 23 with the work thereon into contact with the looped portion 62 between the guide wheels 17 and 18, he performs this stage of operation gradually, raising the form with the work thereon little by little as the traveling belt 10 eats away the surplus material from the edges of the work. In any event the abrading action of the belt 10 is so rapid that in most instances a few rotations of the form 23 is usually sufficient to bring the work to a finished state. It will thus be seen that the present invention provides a machine for sand papering or smoothing articles of the character described efficiently and with great rapidity.

We claim:

1. A machine of the character described comprising, a vertically arranged rotatable

shaft having an annulus-like support on its upper end, an endless belt of abrasive material traveling in a vertical plane, means for supporting and guiding the belt including two lever arms, a guide wheel on each lever arm and over which the lower section of the belt passes, means for yieldingly holding the guide wheels toward each other, one guide wheel lying in a vertical plane without the support and the other guide wheel lying in a vertical plane within the support, and means for raising the support to bring it into contact with the belt section between the guide wheels.

2. In a machine of the character described comprising, a vertical, rotatable shaft, an annulus-like support on the upper end of the shaft, an endless belt of abrasive material traveling in a vertical plane and located over one section of the support, means for supporting and guiding the belt including two lever arms, guide wheels mounted on the lower ends of the lever arms over which the lower section of the belt passes, means for holding the lower ends of the lever arms spaced apart to hold the belt taut, means for raising the support and simultaneously therewith releasing the lever arms to permit the guide wheels to be moved toward each other to form a loop in the lower section of the belt as the support is brought into contact therewith.

3. In a machine of the character described comprising, a vertical, rotatable shaft, an annulus-like support mounted on the shaft, cam surfaces connected with the support, an endless belt of abrasive material, means for supporting and guiding the belt including two lever arms, a guide wheel mounted on each lever arm and over which the lower section of the belt passes, one guide wheel being yieldingly supported on its lever arm, and means carried by the latter lever arm for contacting with the cam surfaces to raise the guide wheel thereon.

4. In a machine of the character described including a rotatable annulus-like support, an endless belt of abrasive material, means for supporting and guiding the belt including two lever arms, one lever arm having a relatively movable lower end and the other lever arm having a jointed lower end adapted to be held in fixed position relatively to the rest of the arm, a guide wheel on each lower end of the lever arms and over which the lower section of the belt passes, and means for moving the lever arms to vary the distance between the guide wheels.

5. In a machine of the character described including a rotatable annulus-like support having a cam path, an endless belt of abrasive material, means for supporting and guiding the belt including two lever arms, one lever arm having a yielding lower end, a guide wheel mounted on each lower end of the lever

- arms and over which the lower section of the belt passes, a roll on the yielding lower end of the first lever arm adapted to ride on the cam path, and means for varying the distance between the guide wheels.
- 5 6. In a machine of the character described comprising a rotatable vertical shaft, an annulus-like support mounted on the upper end of the shaft, an endless belt of abrasive material traveling in a vertical plane, means for 10 supporting and guiding the belt including two lever arms pivotally mounted on substantially the same plane and arranged so that the upper and lower ends of the levers move toward and away from each other simultaneously, means for yieldingly moving the lower ends of the lever arms toward each other, guide wheels mounted on the lower ends of the lever arms and over which passes 15 the lower section of the belt, the vertical plane passing through the other guide wheel being outside the support and the vertical plane passing through the other guide wheel being within the support, means for moving 20 the lever arms to elongate the distance between the guide wheels, means for raising the support, and a common actuating means for moving the lever arms and the support simultaneously.
- 25 7. A machine of the character described comprising, a rotatable vertical shaft, an annulus-like support mounted on the upper end of the shaft, an endless belt of abrasive material traveling in a vertical plane above the 30 support, means for supporting and guiding the belt including two lever arms pivoted on substantially the same plane and having crossed upper ends, the upper extremities of the lever arms having cam surfaces, the lower 35 ends of the lever arms being spaced apart, a guide wheel mounted on the lower end of each lever arm, the lower section of the belt passing under the guide wheels, the lower end of one lever arm being yieldingly mounted on the rest of the lever arm and the lower end of the other lever arm being jointed and adapted to be held in fixed relation with the rest of the lever arm, a cam path connected 40 with the support adapted to be engaged by the yielding lever arm end, a vertically arranged rod, a roll on the upper end of the rod adapted to contact with the cam surfaces of the lever arms, means for actuating the shaft and the rod simultaneously to lower 45 the shaft and bring the roll into contact with the lever arms to increase the distance between the guide wheels, and means for moving the lower ends of the lever arms toward each other when the shaft and rod are raised 50 55 to free the roll from the lever arms and move the support against the belt.
